United States Patent Office

Des. 176,463
Patented Dec. 27, 1955

176,463

BUCKLE

Samuel E. Kelman, Providence, R. I., assignor to Metalart Buckle Co., Providence, R. I., a corporation of Rhode Island

Application April 12, 1955, Serial No. 35,480

Term of patent 3½ years

(Cl. D17—1)

FIG. 1

FIG. 2

FIG. 3

Fig. 1 is a front view of a buckle embodying my new design;

Fig. 2 is a bottom edge view thereof; and

Fig. 3 is a rear view thereof.

The dominant features of applicant's design reside in the portions shown in full lines.

I claim:

The ornamental design for a buckle, substantially as shown and described.
